UNITED STATES PATENT OFFICE.

ADOLPH DIETSCHÉ, JR., OF NEW YORK, N. Y., ASSIGNOR TO AMERICAN LITHOGRAPHIC COMPANY, OF NEW YORK, N. Y., A CORPORATION OF NEW YORK.

DISPLAY DEVICE.

Application filed February 23, 1922. Serial No. 538,692.

To all whom it may concern:

Be it known that I, ADOLPH DIETSCHÉ, Junior, a citizen of the United States, and a resident of New York, borough of Queens, 5 in the county of Queens and State of New York, have invented certain new and useful Improvements in Display Devices, of which the following is a specification.

This invention relates to improvements in 10 display devices, such as are used in connection with containers and has as its object to provide a simple, attractive and inexpensive device for such purposes.

Another object is in the provision of a 15 unitary, easel-like stand so formed as to firmly engage a container or be removed therefrom without the use of extraneous parts or fastenings of any kind and wherein is presented a considerable area for embellishment or advertising if desired.

These improvements comprise features 20 whereby the foregoing objects are attained, as hereafter fully described, reference being had to the annexed drawing, in 25 which:—

Figure 1 is the front perspective view showing a preferred embodiment of my invention, its application being clearly indicated therein.

Fig. 2 is a plan view of the blank prior 30 to bending.

Fig. 3 is a similar view showing in smaller scale a blank modified to conform to a different type of container.

The scale of Figs. 1 and 2 is substantially 35 equal, and the scale of Fig. 3 is about half that of the other figures.

In the construction of the device any relatively thin, flat sheet material capable of 40 bending may be used, the same being shaped by a shearing die essentially as shown in either Figs. 2 or 3, the latter varying only in the shape of the opening.

The blank may have parallel side edges 45 terminating at their upper ends in convergent curves 6 of relatively small radius, these curves blending into a connecting, arcuate curve 7 of relatively large radius, constituting the upper end of the blank.

The lower ends of the side edges 5 may 50 extend to short transverse shoulders 8, connected by an outward curve 9, forming the bottom boundary of the blank.

A bending line 10 extends across the 55 blank between shoulders 8, articulating said

blank into a wall or upper portion 11, and a substantially semi-circular base 12.

Extending upward into the vertical wall portion 11, from the plane of the bending line 10, are preferably parallel inner edge 60 walls 14, the space 15 between said edges being central of the blank and those edges may terminate in short cross cuts 16, joining short longitudinal cuts 17, extending in parallelism towards the base, and presenting 65 spaces or notches 18, the function of which will later be seen herein.

The ends of the cuts 17 are connected by downwardly extending curve 19, forming a tongue 20 bounded at its upper end by a 70 crease or folding line 21, extending transversely thereacross in the plane of the junction of the curved wall 19 and cuts 17.

The lower ends of edges 14 are joined by a curved wall 22, extending into the base 75 and enclosing a space 23, the same being more than half of a circle and having a radius corresponding to that of the container 25, as shown in Fig. 1. The material between the edges 5 and 14, when the 80 blank is bent on the crease line 10, constitute in effect legs 24 as will be seen.

The illustrated container has a dished head, including an inner upstanding wall 85 25' suited to be received in notches 18, when the peripheral wall of the container is in contact with the edges 14, part of its body protruding into the space 15 and its lower portion extending through the opening 23 in the base, which is now bent forwardly 90 at substantially right angles on line 10.

The tongue 20 is bent on line 21 to extend forwardly and act as a stop against container 25, which is obviously entered from the bottom, the tongue also entering 95 the dished top of the container and engaging upstanding wall 25', the inner radius of which is the same as the curve 19 of the tongue.

In Fig. 3 the outline of the blank is the 100 same as that above described but the profile of the opening differs, as it is suited to engage a container having rectangular walls.

To this purpose tongue 20' is angular rather than curved, and the opening 23' is 105 suited to engage a rectangular container in such manner that one of its corners project into the space 15', the adjacent side of the container making contact with the edges 14'.

From the foregoing it will be seen that 110

the shape of the opening in the unitary blank may vary to suit different shapes of containers and that the form, size and proportion of the blank may be very considerably modified without departing from the spirit of the invention as set forth.

I claim:

1. In a display device of sheet material adapted for erection on a container having a dished head including an inner upstanding wall, the combination of a unitary blank having a transverse folding crease there-across, an opening through said blank extending both above and below said crease, said opening having edge walls extending upwardly from said transverse crease, said walls being spaced apart a distance less than the major transverse dimension of the container on which the device is adapted for erection, that portion of said opening extending below said crease having a contour in approximate conformity transversely with more than half of the outer wall of the container, and means articulated to the upper wall of said opening for engagement with the inner upstanding wall of the container head.
2. In a display device of sheet material adapted for erection on a container having a dished head including an inner upstanding wall, the combination of a unitary blank having a transverse folding crease there-across, an opening through said blank extending both above and below said crease, said opening having parallel edge walls extending upwardly from and normal to said transverse crease, said walls being spaced apart a distance less than the major transverse dimension of the container on which the device is adapted for erection, that portion of said opening extending below said crease having a contour in approximate conformity transversely with the greater

portion of the outer wall of the container, and a lip extending downwardly from the upper portion of said opening between said edge walls and articulated to said blank, said lip being adapted for engagement with the inner upstanding wall of the container head.

3. In a display device of sheet material adapted for erection on a container having a dished head including an inner upstanding wall, the combination of an upright member having two downwardly reaching legs, said legs being spaced apart a distance less than the major transverse dimension of the container on which the device is adapted for erection, a U shaped member articulated to the lower ends respectively of said legs, the inner wall of said U shaped member conforming approximately to the outer wall of the container, and means carried by said upright member between said legs, for engagement with the inner upstanding wall of the container.

4. In a display device of sheet material adapted for erection on a container having a dished head including an inner upstanding wall, the combination of an upright member having two downwardly reaching legs, said legs being spaced apart a distance less than the major transverse dimension of the container on which the device is adapted for erection, a U shaped member articulated to the lower ends respectively of said legs, the inner wall of said U shaped member conforming approximately to the outer wall of the container, and a lip articulated to said upright member between said legs and adapted for engagement with the inner upstanding wall of the container.

In witness whereof, I hereby affix my signature this 20 day of February, 1922.

ADOLPH DIETSCHÉ, Jr.
